UNITED STATES PATENT OFFICE.

RASMUS PEDERSON, OF PARKERSBURG, IOWA.

WAGON-LOADING DEVICE.

No. 843,695.

Specification of Letters Patent.

Patented Feb. 12, 1907.

Application filed March 15, 1906. Serial No. 306,192.

To all whom it may concern:

Be it known that I, RASMUS PEDERSON, a citizen of the United States, residing at Parkersburg, in the county of Butler and State of Iowa, have invented certain new and useful Improvements in Wagon-Loading Devices; and I do hereby declare the following to be a full, clear, and exact description of the invention, such as will enable others skilled in the art to which it appertains to make and use the same.

My invention has for its especial object to provide an improved device for loading manure into a wagon; and to the above ends it consists of the novel devices and combinations of devices hereinafter described, and defined in the claims.

The invention is illustrated in the accompanying drawings, wherein like characters indicate like parts throughout the several views.

Figure 1 is a plan view showing a wagon having my improved device applied thereto. Fig. 2 is a side elevation of the parts shown in Fig. 1. Fig. 3 is a detail taken in section approximately on the line $x^3 x^3$ of Fig. 1, showing particularly one of the fixed guide-rails and coöperating tripping devices, some parts being broken away and others being removed. Fig. 4 is a detail view in side elevation, illustrating the action of one of the trip devices on the fork. Fig. 5 is a transverse section on the line $x^5 x^5$ of Fig. 4. Fig. 6 is a view of the wagon and attachments, principally in front elevation, but with some parts sectioned on the line $x^6 x^6$ of Fig. 2 and with some parts removed. Fig. 7 is a detail view showing a modified form of certain of the parts that are applied to the adjustable rail-sections of the device, and Fig. 8 is a view showing a wagon diagrammatically in rear elevation and showing a modified form of my improved device applied thereto.

Referring to the drawings, the numeral 1 indicates the body, the numeral 2 the rear wheels, the numeral 3 the front wheels, the numeral 4 the pole; and the numeral 5 the seat of the wagon, which wagon is preferably provided with a manure-spreading device of the ordinary or any suitable construction, the discharge-cylinder 6 only of which is shown. It may be here stated that my invention will usually be applied to wagons having manure-spreading devices, the primary purpose of my invention being to effect the rapid loading of such wagons and to

thereafter unload the wagons by means of the manure-spreading devices, which manure-spreading devices, however, form no part of my present invention.

Referring now to my improved attachment, the loading device, the numeral 7 indicates a pair of laterally-spaced guide-rails that are rigidly supported one on each side of the wagon-box by means of vertical legs or posts 8, which, as shown, detachably fit in socket-brackets 9, secured on the sides of said box. Pivoted to the rear end of each rail 7 is a vertically-adjustable rail 10, the lower end of which is preferably curved upward and rearward. These rails 10 are adapted to be set in various positions, either inclining downward or extending upward or in horizontal direction, so as to raise their curved ends upon the manure piles of different heights.

On the extreme upturned ends of the rails 10 are mounted guide-sheaves 11, and lower down on said rails are guide-sheaves 12. At the pivotal joints between the rails 7 and 10, but laterally offset outward therefrom, are guide-sheaves 13. On several of the rail-supporting legs 8 are guide-sheaves 14. Mounted in suitable bearings on top of and at the front of the box 1 is a transverse shaft 15, which carries at its ends outward of the box and in line with the sheaves before noted driving sheaves or drums 16.

For picking up and carrying the manure I provide a fork or toothed scoop 17, the tines 18 of which are all rigidly secured to a transverse bail 18, the trunnion portions of which have journalized thereon flanged truck-wheels 19, that are adapted to run over rails 7 and 10. Also working loosely on each trunnion of the bail 18 are flat non-rotary shoes 20, that stand in the same plane with the sheaves above noted. On each side of the wagon-box are operating-cables 21, the ends of which are attached to the corresponding shoes 20 on opposite sides of the trunnions of the bail 18. These cables 21 are passed over the guide-sheaves 13, 11, 12, and 14 and are given several wraps around the corresponding driving-drums 16, so that they will be positively moved when said drums are rotated. To take up the slack of the cables 21, weighted floating sheaves 22 are mounted thereon between two of the guide-sheaves 14, as best shown in Fig. 2. The free ends of the rails 10 are preferably provided with ground-wheels 23, which adapt the said rails to be

dragged over the ground when it is desired to pick up scattered manure under a forward movement of the wagon.

The shaft 15, which carries the driving drums 16, is adapted to be rotated in two different ways—to wit, either by a hand-operated lever or by horse-power. The hand-lever driving mechanism, as shown, comprises as follows: On one end of the shaft 15 is a sprocket 24, and mounted in suitable bearing-brackets 30 and 30^a on the front end of the box 1 is a counter-shaft 25, that is provided at one end, in line with the sprocket 24, with a sprocket 26, over which and said sprocket 24 runs a sprocket-chain 27. The inner end of the shaft 25 terminates over the pole 4 and is provided with a spur-pinion 28, that meshes with a spur-gear 29, mounted on said bracket 30. The numeral 31 indicates a latch-lever which is pivoted to the bracket 30 in line with the axis of the gear 29 and is adapted to be locked in any desired position to a notched segment 32, formed as part of the bracket 30. The lever 31 carries a reversible driving-pawl 33, that is adapted to work upon the teeth of the wheel 29 to drive the same in either of two directions, according to the position in which said pawl is set.

By means of the hand-lever 31 and connections just described the two cables 21 may be driven in either direction, so as to cause the fork to travel from a filling position at the free ends of the rails 10 to a dumping position on the rails 7 above the box 1 or from a dumping position back to a filling position.

The horse-power driving device, as shown, is as follows: Rigidly secured to one side of the gear 29, or otherwise secured to the shaft 25, is a large sheave 34, to which is attached one end of a cable or flexible connection 35. The other end of this cable 35 is anchored to a lug 36, rigidly secured on the rear end of the pole 4. The intermediate portion of said cable 35 passes under a guide-sheave 37 on a depending portion of the bracket 30 and over a guide-sheave 38, which is mounted on an arm carried by the equalizing-beam 39 of a two-horse evener. This equalizing-beam 39 is pivoted to a yoke-like guide-head 40, that is mounted to slide on the rear portion of the pole, but is normally held rearward against forward sliding movement, as shown, by a pin 41, that is inserted in a suitable seat in the pole. As shown, a metallic guide-strap 42, secured at its ends to the top of the pole 4, overlies the equalizing-beam 39 and limits its extreme sliding movements. Springs 43, attached to the equalizing-beam 39 and to the rear end of the pole, yieldingly draw the said beam rearward. On the forward end of the pole is a neck-yoke 44, that is provided with a neck-yoke ring 45, that adapts it to slide upon the pole. A long rod 46 underlying the pole connects the neck-yoke ring

45 to the head 40, and thus connects the neck-yoke and equalizing-beam, so that they will slide together on the pole. In Fig. 2 the neck-yoke is shown as near the end of the pole; but with the equalizing-beam secured in its rear-most position said neck-yoke should be far enough back on the pole so that under a forward movement of the equalizing-beam it will not be moved off from the forward end of the pole.

At different points along the fixed rails 7 are pivoted fork-tripping arms 47, which when raised will engage with trip-fingers 48, that project in offset directions from the crank or swinging body portion of the bail 18 of the fork 17. As shown, there are three of these trip-arms 47 on each of the rails 7, and they are arranged in transversely-alined pairs, so that the members of a given pair will act simultaneously on the two trip-fingers 48 of the said bail 18. The trip-arms 47 that are most forward normally stand in position to engage the said trip-fingers 48, but those that are farther rearward normally stand in inoperative positions below the lines of travel of said trip-fingers 48. These are connected by light rods 49, the forward ends of which are attached to arms 50 of a rock-shaft 51, that is mounted in suitable bearings on the upper forward portion of the wagon-box 1. This rock-shaft 51 is provided with a footpiece 52, which when stepped upon will rock said shaft and raise the rear and intermediate trip-arms 47 into operative positions. In Fig. 4 one of the trip-arms 47 is shown in an inoperative position by full lines and in an operative position by dotted lines. By reference to this view it will be seen that as the fork is moved forward and the trip-fingers 48 are thrown against the raised trip-arms 47 said fork will be tipped into a dumping position. (Shown by dotted lines at the left in Fig. 2.) If the operator wishes to dump the load from the fork at the rear portion of the box, he must raise the rear trip-arms 47 (and incidentally the intermediate arms 47) before the fork reaches the said rear arms. If he wishes to dump the load at the intermediate portion of the box, he should wait until after the fork has passed the rear trip-arms 47 and then should raise the intermediate trip-arms 47 (and incidentally the rear arms 47.) The most forward trip-arms 47 normally stand in position to dump the load; but if for any reason it should be desirable to carry the load farther toward the front the said forward trip-arms may be moved pivotally forward and downward into inoperative positions.

When the fork is moved down to the free ends of the rails 10, it may by a person standing in the vicinity thereof be caused to take up the load by a forward rocking movement. As the fork is drawn over the points of pivotal connection between the rails 6 and 10

the shoes 20 will slide freely over guide-sheaves 13. The weighted sheaves 22 take up the slack of the driving-cables 21 and permit the free pivotal movements of the rail-sections 10 from lowered to raised positions.

The usual way of lifting the loaded fork is to cause the horses to draw the equalizing-beam 39 forward, and thereby through the flexible connection 35 and intermediate connections to the cables 21 raise the loaded fork onto the fixed rail 7. Approximately one foot and a half of the sliding movement of the beam 39 will through the connections described be sufficient to raise the loaded fork onto the rails 7. In this way the horses are caused to perform the hardest part of the work in lifting the loaded fork. Then by one or more reciprocating movements of the lever 31 the loaded fork may be moved over the rails 7 and dumped at the proper point, and thereafter by a reverse ratchet action of the said lever on the gear 29 the empty fork may be returned to a position for loading.

In Fig. 2 at the right the fork is shown as turned into a reverse position from that shown elsewhere in said view. Otherwise stated, the fork is turned with its tines projecting rearward. It may be desirable in some cases to set the fork in this position, so that it may be made to take a load from the side of the stack.

In the modification shown in Fig. 7 the guide-sheave 12 is not employed; but in lieu thereof the cable 21 is run through a curved tubular guide 53, secured to the curved free end of the rail 10.

In the modification shown in Fig. 8 the adjustable rail-sections 10 are shown as pivoted to the rails 7^a, that extend transversely over the top of the wagon-box, and are provided at their central portions with tripping-fingers 47^a. The said rails 7^a are secured to connecting-supports 54, that are provided with flanged wheels 55, that run on the upper edges of the sides of the wagon-box, so that the entire device is adapted to be moved from front to rear of the box. In this instance the cables 21^a, which may be operated in any suitable way, are attached to the shoes 20 of the fork.

The device described may of course be used for loading various materials into wagon-boxes, and, if desired, the so-called "forks" may be made in the form of scoops adapted to pick up and carry sand or similar

material. In some instances it may be desirable to remove the pivoted truck-rails 10 after the wagon has been loaded, and this may be done by removing the bolts that pivotally connect the rails 7 and 10. This being done, the fork may be removed, and the loose portions of the operating-cables 21 may be hung upon hooks 56 on the sides of the wagon-box. (Shown by dotted lines in Fig. 2.)

What I claim is—

1. The combination with a wagon, of track-rails extending therefrom to a position for loading, a fork or scoop mounted to travel over said track-rails, from a position for filling into a position for dumping into the wagon-box, and trips located at different points and arranged to intercept said fork or scoop and cause the same to dump its load into the wagon-box, substantially as described.

2. The combination with a wagon, of track-rails extending therefrom to a position for loading, a fork or scoop mounted to travel over said track-rails, from a position for filling into a position for dumping into the wagon-box, a cable attached to said fork or scoop at both ends, a draft-equalizing beam mounted to slide on the wagon-pole, and driving connections between said equalizing-beam and said cable, whereby the power of the horses is rendered available for causing the loaded fork or scoop to travel over said track-rails, and a device operative on said cable to impart return movements to said fork or scoop, substantially as described.

3. The combination with a wagon, of track-rails extending therefrom to a position for loading, a fork or scoop having a crank-like bail with wheels on its trunnions, which wheels run over said track-rails, a cable attached to said fork, for causing the same to travel over said rails, and trip-fingers located along certain of the track-rails, in position to engage the crank portion of said bail, and cause said fork or scoop to rock and dump its load into the wagon-box, substantially as described.

In testimony whereof I affix my signature in presence of two witnesses.

RASMUS PEDERSON.
